ELECTRIC PLUG AND SOCKET

Horace R. Ellis, Meadville, Pa.

Application April 26, 1937, Serial No. 139,043

12 Claims. (Cl. 173—330)

This invention relates to electrical connections and has special reference to a plug and socket connection for connecting a two wire flexible cable to a pair of feed wires.

5 The ordinary connection of this character consists of a plug having a pair of stiff prongs fixedly carried thereby and adapted to enter a socket having a pair of contacts fixed therein whereby the prongs engage upon entering the socket. 10 Such devices depend entirely upon friction to hold them together. These frictionally held connections are peculiarly apt to separate under the stresses induced by pulls on the cable such as often occur when the flexible cable is used for 15 connecting such an instrumentality as an electrically heated iron to a house circuit since the user of the iron frequently tightens the flexible connection.

It is one important object of the present invention to provide a novel and improved prong connection of this general type wherein the arrangement is such that the connection does not depend solely on friction to hold its elements together but an additional holding function is effected by flexing of the prongs.

A second important object of the invention is to provide socket means, in such a connection, whereby the prongs inserted therein are caused to take a sinuous path.

30 A third important object of the invention is to provide a novel arrangement of this character which may be used with any existing socket for a two-prong plug.

A fourth important object of the invention is 35 to provide a novel socket attachment adapted to be secured over an ordinary two-prong socket and which will cause flexing of the prongs of a plug as they are inserted in the socket.

With the above and other objects in view the 40 invention consists in general of certain novel details of construction and combinations of parts hereinafter fully described, illustrated in the accompanying drawing and pointed out in the appended claims.

45 In the accompanying drawing like characters of reference indicate like parts in the several views and

Figure 1 is a front elevation of the device with its parts assembled.

50 Figure 2 is a section on the line 2—2 of Figure 1.

Figure 3 is a face view of the plug element of the device.

55 Figure 4 is a section on the line 4—4 of Figure 2.

Figure 5 is a section on the line 5—5 of Figure 2.

Figure 6 is a fragmentary view showing the face of the socket element of the device.

Figure 7 is a side elevation of the plug element 5 of the invention disconnected from the socket.

In the embodiment of the invention as here shown the device includes a plug element 10 and a socket element 11. The plug element consists of a semi-ovate body 12 of insulating material. 10 In the front or face of the body is a circular recess 13 from which extends an axial bore 14 having an enlargement 15 opening into the recess 13. This provides a flat annular surface 16. On this surface is seated a pair of arcuate prong bases 17 which are fixed in place by tubular rivets 18 molded into the body 12. These bases 17 are disposed diametrically opposite each other and each carries a binding screw 19 adjacent one end so as to provide means for connecting the two wires 20 of a flexible cable. The remaining ends of the bases 17 have a pair of parallel prongs 20 which are of standard width and spacing. These prongs are made of thin flexible metal preferably having a considerable degree of resiliency. These 25 prongs are straight when disconnected from the socket 11 as is shown in Figure 7.

The socket is preferably molded unitarily from a suitable insulating material such as a synthetic resin, Bakelite being a suitable material for the 30 purpose. This socket consists of a base portion 21 having a boss 22 projecting from its center.

Through this socket extends a pair of prong passages having aligned end portions 23 and outwardly bowed central portions 24 connected to 35 the ends 23 by curved portions 25. The outer end portions are provided with flaring mouths 26. There is thus formed a pair of sinuous prong passages and these passages are spaced at their ends to conform to the spacing of the prongs 20 and these prongs are of sufficient length to project far enough through the base 21 to enter a standard socket, indicated typically at 27, and engage the contacts 28 thereof. The base 21 is provided with screw-holes 29 for the reception of 40 screws 30 engaging in wall 31 or the like so that the socket 11 can be secured over the socket 27 with the prong passages 22, 23, 24 in registry with the openings of said socket 27.

It will be plain from Figure 2 that the insertion 50 of the prongs in the sinuous passages causes the flexible prongs to assume a sinuous shape for portions of their length, this being effected against the tendency of the prongs to remain straight. The resiliency of the prongs causes 55

them to bind in the passages and thus the plug is held very securely to the socket 11 and will not become accidentally disengaged.

What is claimed is:

- 5 1. In a connector for electric wiring, a plug body having a plurality of prongs extending therefrom each consisting of a thin strip of readily flexible material, socket means having a plurality of prong passages for receiving said 10 prongs, said passages having aligned end terminal portions and offset intermediate portions to cause the flexing of the prongs intermediate their ends when inserted into said passages, said passages extending entirely through said socket 15 means and the prongs being of sufficient length to project beyond the socket means to enter a standard socket, and means for securing said socket means on a standard socket with said passages registering with the prong openings of the standard socket.
- 20 2. In a connector for electric wiring, a plug body having a plurality of normally straight prongs projecting therefrom, said prongs each consisting of a thin strip of readily flexible conductive material, socket means having a plurality of prong passages for receiving said prongs, said 25 passages having endwise aligned end terminal portions and offset intermediate portions to cause the flexing of the prongs intermediate their ends when the prongs are inserted into the passages, the offset intermediate portions of the passage being disposed in oppositely extending relation, said passages extending entirely through said socket means and the prongs being of sufficient 30 length to project beyond the socket means to enter a standard socket, and means for securing said socket means on a standard socket with said passages registering with the prong openings of the standard socket.
- 35 3. In a connector for electric wiring, a plug body having a plurality of normally straight prongs projecting therefrom, said prongs each consisting of a thin strip of readily flexible conductive material, socket means having a plurality of 40 sinuous prong passages for receiving said prongs, said passages extending entirely through said socket means and the prongs being of sufficient length to project beyond the socket means to enter a standard socket, and means for securing said socket means on a standard socket with said 45 passages registering with the prong openings of the standard socket.
- 45 4. In a connector for electric wiring, a plug body having a plurality of normally straight prongs projecting therefrom, said prongs each consisting of a thin strip of readily flexible conductive material, socket means having a plurality of 50 sinuous prong passages for receiving said prongs, the material of the prongs being sufficiently resilient to restore the prongs to their normally straight condition upon withdrawal from said passages, said passages extending entirely through said socket means and the prongs being of sufficient length to project beyond the 55 socket means to enter a standard socket, and means for securing said socket means on a standard socket with said passages registering with the prong openings of the standard socket.
- 60 5. In a connector for electric wiring, a plug body having a plurality of prongs extending therefrom, each consisting of a thin strip of readily flexible material, and socket forming means having a plurality of passages extending from end to end thereof for receiving said prongs 65 and each consisting of a pair of endwise aligned 70 end terminal portions merging at their inner ends into curved portions terminating in a bowed portion, the said several portions of each passage coacting to cause the flexing of a prong, intermediate its ends when inserted into the passage, 75 said prongs being of a length to extend from said means to enter a standard socket forming element to make electrical contact in the latter. 5
- 75 6. In a connector for electric wiring, a plug body having a plurality of prongs extending therefrom, each consisting of a thin strip of readily flexible material, and socket forming means having a plurality of passages extending from end to end thereof for receiving said prongs and each consisting of a pair of endwise aligned 10 end terminal portions merging at their inner ends into curved portions terminating in a bowed portion, the said several portions of each passage coacting to cause the flexing of a prong, intermediate its ends when inserted into the passage, 15 said prongs being of a length to extend from said means to enter a standard socket forming element to make electrical contact in the latter, the bowed portions of said passages being oppositely disposed. 20
- 80 7. In a connector for electric wiring, a plug body having a plurality of prongs extending therefrom, each consisting of a thin strip of readily flexible material, and socket forming means having a plurality of passages extending from end to end thereof for receiving said prongs and each including a pair of inner endwise aligned end terminal portions and an outwardly directed bowed shaped central portion, the said several portions of each passage coacting to 30 cause the flexing of a prong, intermediate its ends when inserted into the passage, said prongs being of a length to extend from said means to enter a standard socket forming element to make 35 electrical contact in the latter. 25
- 85 8. In a connector for electric wiring, a socket member for mounting on a standard socket forming element having passages extending from end to end thereof, and a plug formed with continuous contact prongs of strip-like form of greater length than and for extension through said passages and of a length to extend into said element to make electrical contact therewith, said prongs being formed of readily flexible material, said passages being formed with offset 50 portions intermediate their ends to cause the flexing of the prongs, intermediate their ends when the prongs are inserted in the passages. 40
- 90 9. In a connector for electric wiring, a socket member for mounting on a standard socket forming element having passages extending from end to end thereof, and a plug formed with continuous contact prongs of strip-like form of greater length than and for extension through said passages and of a length to extend into 55 said element to make electrical contact therewith, said prongs being formed of readily flexible material, said passages being formed with offset portions intermediate their ends to cause the flexing of the prongs, intermediate their ends 60 when the prongs are inserted in the passages, said offset portions being oppositely disposed and directed outwardly with respect to the remaining portions of said passages. 65
- 95 10. In a connector for electric wiring, a socket member for mounting on a standard socket forming element having passages extending from end to end thereof, and a plug formed with continuous contact prongs of strip-like form of greater length than and for extension through 70 said passages and of a length to extend into 75 said element to make electrical contact therewith, said offset portions being oppositely disposed and directed outwardly with respect to the remaining portions of said passages. 75

said passages and of a length to extend into said element to make electrical contact therewith, said prongs being formed of readily flexible material, said passages being formed with offset portions intermediate their ends to cause the flexing of the prongs, intermediate their ends when the prongs are inserted in the passages, the cross section area of said offset portions being such to provide for the walls of the passages to snugly engage the prongs.

5 11. In a connector for electric wiring, a socket member for mounting on a standard socket forming element having passages extending from end to end thereof, the intake end or mouth of each passage being flared, each passage being formed with endwise aligned end terminal portions and an intermediate portion offset with respect to its aligned end terminal portions, and a plug formed with continuous prongs of strip-like form of greater length than and for extension through said passages and of a length to

extend into said element to make electrical contact therewith said prongs formed of normally non-flexed readily flexible material, said offset portions causing the flexing of the prongs intermediate their ends when the prongs are extended 5 through the passage.

12. In a connector for electric wiring, a plug body having a plurality of flexible strip-like prongs extending therefrom and a socket forming means having a plurality of passages extending from end to end thereof for receiving said prongs, the configuration of said passages being such as to bow the prongs intermediate the ends thereof said means including an annular flange provided with openings for the passage of hold-fast devices for anchoring it in juxtaposition to a standard socket forming element, and said prongs being of greater length than said passages and of a length to extend into and make electrical contact in said element. 10 15 20
